The United States of America,

to all whom these Letters Patent shall come:

William J. French, a citizen of the United States, hath alleged that he has invented a new and useful improvement in a wire and filament wire for drawing with a drawing machine and an a brush.

Which improvement he aforesaid has not been known or used before his application, hath made oath that he doth truly believe that he is the true inventor or discoverer of the said improvement, hath paid into the treasury of the United States the sum of thirty dollars, delivered a receipt for the same, and presented a petition to the Secretary of State, signifying a desire of obtaining an exclusive property in the said improvement, and praying that a patent may be granted for that purpose. These are therefore to grant, according to law, to the said William J. French, his heirs, administrators and assigns, for the term of fourteen years, from the aforesaid day of December, one thousand eight hundred and sixteen, the full and exclusive right and liberty of making, constructing, using, and vending to others to be used, the said improvement; a description whereof is given in the words of the specification annexed to and forming a part of this patent, in the schedule hereunto annexed, and is made a part of these presents.

In Testimony whereof, I have caused these Letters to be made Patent, and the Seal of the United States to be affixed thereto.

W. F. B. S. Under my hand, in the City of Washington, this twentieth day of December, in the year of our Lord the Thousand Eight Hundred and sixteen, and of the Independence of the United States of America, the forty-first.

John B. Thompson,

BY THE PRESIDENT.

John B. Thompson,

Secretary of State.

City of Washington, To Wm.

I HEREBY CERTIFY, That the foregoing Letters Patent were delivered to me on the twentieth day of December, in the year of our Lord, One Thousand Eight Hundred and sixteen, and were presented to me for my signature, and that I have examined the same, and find them conformable to law, and to be hereby given the name of the Secretary of State, within these dates from the date aforesaid, as well as the day and year aforesaid, in the year aforesaid.

Richard V. Woods,

Attorney General of the United States.

the first time in the history of the world, the people of the United States have been called upon to decide whether they will submit to the law of force, and let a一小部分 of their country be destroyed, or whether they will, in the spirit of the Declaration of Independence, assert their right to self-government, and save their country.

United States Patent

Patent No.: 2752

THE PRACTICE